UNITED STATES PATENT OFFICE

VERNON WESLEY MACISAAC, OF MONTREAL, QUEBEC, CANADA

CENTRIFUGAL SEPARATOR

Application filed March 21, 1930. Serial No. 437,754.

The invention relates to a centrifugal separator as described in the present specification and illustrated in the accompanying drawings that form part of the same.

The invention consists essentially of the novel features of construction pointed out broadly and specifically in the claims for novelty whereby the progress of the material into, through and out of the bowl is facilitated.

The objects of the invention are to segregate certain heavier materials from the main body fed and deposit it in pockets, thus relieving the machine from time to time during the operation as well as removing lighter impurities continuously, thereby effecting a great saving in time and labor and insuring greater efficiency; to promote the separation in an unique manner of heavy and light impurities from fibrous pulps such as paper stock and from non-fibrous pulps such as fluid suspensions of mineral particles and the classification thereof by centrifugal sedimentation; to avoid interruptions caused by comparatively frequent stoppages for removal of sediment and reduce the liability of picking up impurities in the outward flow of presumably pure liquid pulp; to regulate the rotation of the rotary members in order that the constant or intermittent progression of the heavier material will readily accumulate the material in the pockets, from which it is readily accessible for removal; to facilitate the mechanical operation of the machine parts by contributing to maintenance of motion through the recovery of energy at the discharge; and generally to provide in centrifugal separating machines a construction that will lend itself to the furthering of the separation and the scavenging of the machine while in motion through relieving the machine of heavier and lighter reclaimable or waste material and that will effect economy in the consumption of power and increased efficiency throughout.

In the drawings, Figure 1 is a vertical sectional view of a form of centrifugal machine adapted to various purposes showing a means of discharging heavier material during rotation.

Figure 2 is a cross sectional view on the line 2—2 in Figure 1.

Figure 3 is a cross sectional view on the line 3—3 in Figure 1.

Figure 4 is a detail of a valve and stem.

Figure 5 is a detail of another form of valve and stem, such as shown in Figure 6.

Figure 6 is a vertical sectional view of a modified form of bowl showing another arrangement of pockets and valves and a means of recovering power.

Figure 7 is a cross sectional view on the line 7—7 in Figure 6.

Figure 8 is an exterior view showing the inner shell and spiral scraper in the form of the invention illustrated in Figure 1.

Like numerals of reference indicate corresponding parts in the various figures.

In the separation of solids from liquids, heavier liquids from lighter liquids and any heavier material from lighter materials, the use of the centrifugal machine is widely known, therefore modern developments have largely to do with the shape of the bowl, the progression of the materials, the discharge and disposition of the separated material and the operation of the bowl to effect the separation economically and with reduction of power.

This invention resides in the fact that the features which have been just mentioned are taken into consideration and particular attention given to the stabilization of machine parts, to the acceleration of the separation and discharge of material; to the regulation of variable speeds where found desirable, to the withdrawal of separated constituents continuously during the operation and to the adaptation of means for the reduction in power.

Referring to the drawings, and particularly to the invention as illustrated in Figure 1, the bowl 15 is of frusto-conical shape being cylindrical at the inlet end 16 and bell shaped outwardly from said inlet end, as indicated by the tapering portion 17 within which the sedimentation occurs.

The bell shaped portion 17 of the bowl flares outwardly at the extreme outward end 18 and is flanged at 19.

The cover 20 is flanged at the outer edge 21 and forms with said flare an annular recess 22 from the inner side.

The cover is rigidly secured to the bowl, being bolted thereto through the flanges and the said recess is a depository for the sedimentation that is eventually worked up from the inlet end of the bowl.

A number of pockets 23 extend outwardly from the recess 22 at intervals around the bowl and these pockets have the relief openings 24.

The cover 20 is formed with the central discharge opening 25 encircling the main shaft 26, and this opening 25 is restricted in relation to the diameter of the bowl at the narrowest portion thereof, that is to say, the diameter of the opening 25 is considerably less than the diameter of the cylindrical end of the bowl, and it is over the edge of this opening 25 that the discharge occurs, this discharge taking place along the plane, indicated by the arrows "P—P".

It is to be noted that the diameter of the discharge opening determines the annular depth of the liquid within the bowl, as centrifugal forces acting on the bowl and its contents tend to force the liquid into a ring against the wall of the bowl, and maintain an approximately cylindrical inner diameter of liquid about equal to the diameter of the discharge opening 25.

Because of the predominance of centrifugal forces over that of natural gravity (ordinarily being from 300 to 500 times gravity) the liquid will be maintained with an inner diameter approximating the inner diameter of the discharge opening, whether the machine is operated with the bowl and shaft 26 vertical or horizontal or in any intermediate position.

The hub 27 is preferably keyed to the main shaft 26 and rigid with the cover 20 through suitable arms not shown.

The inlet end of the bowl is secured to the hub 28 rotatably mounted on the main shaft 26 and containing the inlet passage 29 encircling the shaft 26, the outer wall of the inlet being joined to the hub proper by the radial arms 30, said outer wall having the annular flange 31 through which the bowl 15 is suitably bolted to the outer hub wall.

The main shaft 26 is suitably mounted and driven and is encircled by the tubular mounting or sleeve shaft 32 extending in the lighter

sleeve shaft 34 projecting loosely through the hub 28 beyond the bowl at the inlet end.

The shell 35 is secured to the radial arms 30 and is flanged inwardly at the outer end 36 and at the inner end 37, thus the shell being securely fastened to the radial arms 30 may rotate with the shaft 26 or rotate freely thereon, that is to say, the sleeve shaft 32 may be fixed in its mounting on the shaft 26 or may turn thereon, according to the circumstances of use and in the drawing and in this description this sleeve shaft is journaled to rotate on the said shaft 26.

The shell serves the purpose of checking the flow of liquid in direct lines from the inlet to the discharge of the bowl and of deflecting it outwardly in a thin layer between the bowl and the shell, the thickness of this layer through which the subsided particles must pass being of great importance in the functioning of centrifugal machines, as well as making it possible to reduce the outlet diameter and to effect a saving in the consumption of power.

The sleeve shaft 32 is rotatably mounted on the bush nut 38 screwed on to the shaft 26 thereby affording endwise adjustment for the sleeve shaft and consequently for the shell and regulating the thickness of the layer of liquid being treated between the shell and the bowl.

The outwardly flaring portion or bell shape of the bowl 15 tends to permit particles subsided on the inner surface of said bowl to move more readily towards the recess 22 or collector channel giving them in effect a down hill motion which is preferably assisted by scrapers.

The flexible scraper strip 39 is loosely wound within the bowl 15 and secured at its ends to the rotating shell 35 thus forming a spiral scraper resting on the inner surface of the bowl, so that the said scraper will rotate at a slower angular velocity than the bowl, and thus will move the particles forwardly and outwardly towards the collector channel or recess 22 being a backward rotation induced principally by the negative torque, of acceleration of inflowing liquid emanating from the acceleration dished plate 40 or deflector as it may be called.

This acceleration plate 40 is of circular form and dished and rigidly secured to the bottom of the inner radial extension from the sleeve shaft 32, the vanes 41 extending outwardly from the disc centre 42 and projecting from the dished wall 43, consequently as the liquid enters the inlet 29 it flows on to the dished wall 43 near to the disc centre 42 from which it spreads on to the dished wall 43 between the vanes 41 and in thus entering, the liquid flowing on to the plate 40 has a distinct influence on the speed of the shell besides accelerating the flow in the carrying out of the centrifugal action.

It is to be noted that this speeding up or acceleration of the incoming liquid can only be performed at the expenditure of considerable energy and by powerful reaction on the vanes 41 and that in such machines a large portion of the power is consumed in so accelerating the continually inflowing liquid so that a strongly resistive torque opposing rotation is imparted to acceleration member 40 and thence to 32, 30, 35 and 39 when it is rotating (as it is constrained to do) at a speed nearly equal to that of the bowl 15.

This feature is to be noted particularly in that it is used in a unique manner to supply speed control of the inner parts in relation to the bowl, principally within the bowl rather than principally through external gearing and provides the whole or a principal part of the torque required to backwardly rotate scraper members in relation to the outer bowl, thereby making the regulation of said differential speeds easy of accomplishment with small and cheap differential gearing apparatus.

The speed control for the shell outside of the bowl is in the form of very simple differential gear mechanism in which the internal gear 44 is rigidly mounted on the sleeve shaft extension 34, and this internal gear coacts with the spur gear 45.

The internal gear 46 is keyed to the main shaft 26 and in position opposes the internal gear 44.

The spur gear 47 coacts with the internal gear 46 and the two spur gears 45 and 47 are fixedly mounted on a common shaft 48, this shaft 48 being journaled in the fulcrum member 49, rotatably mounted and supported on the internal gear 46, this rotation of the fulcrum member 49 on the internal gear 46 being controlled by the friction of the brake band 50, suitably arranged for operation in any conventional manner.

The ratio of the gear 45 to the gear 44 differs slightly from the ratio of the gear 47 to the gear 46, so that if the member 49 is fixedly held from rotation by the brake band 50, the motion of the main shaft 26 through the gear 46 will permit the gear 44 to travel only at a different angular speed from the shaft 26, as fixed by the gear ratios built into the mechanism, hence the shell 35 will rotate at a different angular speed from the shaft 26 and the bowl.

The partial release of the brake will permit the fulcrum member 49 to travel about with the internal gear 46, assuming frictional resistances within the mechanism are so balanced as to permit this, but at a less speed than the internal gear 46, so that the difference of speed between the shaft 26 and the shaft 32 will be lessened as the speed of the fulcrum member approaches that of the internal gear, and when the brake band is sufficiently released so that the fulcrum member

travels at the same speed as the internal gear and shaft 26, then no rotation of the gear 47 will take place relative to the gear 46 and the whole differential mechanism will rotate as a unit, therefore the shell 35 and scraper 39 will rotate uniformly with the bowl.

The discharge of the machine is as before stated, through the central opening 25 restricted in relation to the diameter of the bowl, that is to say, the liquid flows inwardly to this discharge opening hugging the inner wall surface and in passing, it must find the passages 51 which are made through turbine blades or divisions 52 in an annular row adjacent to the edge of the central discharge opening.

This formation from the inner wall surface of the cover 20 is between the inner wall surface and the ring 53, and constitutes an inner recovery turbine feature introduced in the path of the outflowing liquid.

This liquid flows around the edge of the opening and through the passage 54 between the turbine blades or divisions 55 closed in by the ring 56 and constituting the outside recovery turbine feature in the path of the discharge, thus considerable energy is recovered from the outflow of the liquid.

The skimmer 57 extends from the underside of the ring 53, around the mouth of the passages 54 leaving sufficient space for the ingress of the thinner liquid to outside turbine, and this skimmer, which may be in sections forming spouts or a complete ring, or in any other shape which will accomplish the purpose, separates the froth or foam containing light impurities or reclaimable matter and directs them over and beyond the outer wall of the ring 56.

A ball valve 58 in each of the pockets 23 seats on the outlets 24 and the stems 59 extend from the ball valve 58 through to the rocker arms 60, being pivotally secured to said valves and rocker arms.

These stems 59 extend through the skimmer or between spouts forming the skimmer to the rocker arms 60, which are pivotally secured to the hub 27. The collar 61 is slidably mounted on the shaft 26, and has the flaring inner end 62 forming a cam face engaging the inwardly offset sections 63 of the rocker arms 60, said offset sections 63 being preferably centrifugally balanced by the weights 64 in the direction of the collar 61.

The sliding collar 61 operates just as many rocker arms as there happen to be valves to correspond to the number of pockets and these stems and valves and rockers are arranged to balance one another. The sliding collar carries a pin 65 extending inwardly in a corresponding slot 66 in the shaft 26 and the pins 65 engage the operating rod 67 which is slidably arranged in the centre of the shaft 26. As to whether this rod is operated manually or automatically is entirely

a matter of choice for the manufacturer or constructor.

The intake 68 is connected by the tubular extension 69 to the source of material to be separated, and extends to form the annular intake chamber 70 which empties into the inlet 29 at 71, through which it reaches the interior of the bowl 15.

The inner shell 35 is preferably of light material and is supported from its tubular mounting as explained and as this mounting extends into the differential gear mechanism the tubular mounting or sleeve shaft 32 will rotate on its journalling on the bush nut 16 at the desired speed.

The actual shell 35 terminates at the inner end in the inwardly extending flange 37 and at the outer end in the inwardly extending flange 36, the flange 36 projecting slightly beyond the edge of the discharge opening.

The accelerator plate 40 may pass beyond the flange 37 and leave a narrow opening 72 between itself and the flange 37 through which foam may pass carrying the light impurities or particles within the shell.

At the outer end of the shell, the drag links or pushers 73 are flexibly secured to said shell and the sweeper ends 74 of these drags are in proximity to the inturned flange of the head 20, consequently in rotation these drags sweep the material in the collector channel or recess 22 into the pockets, from which it is relieved by the operation of the sliding collar 61 and the consequent removal of the valves 58 from their seats.

In Figure 6, the bowl 75 is mounted on the shaft 76 and is slightly different in shape and is formed in the interior with an inwardly extending flange 77 immediately above the pockets 78 in an annular recess 79 intermediate of the length of the bowl 75, said pockets having the relief openings 80 and the ball valves 81 closing said openings.

The ball valves 81 are supported and operated by the stems 82 pivotally secured thereto and secured to the sliding collar 83 mounted on the main shaft 76.

The collar 83 is connected by the rods 85 to the slidable sleeve 86 which is operated by collar 87 the particular operating gear being here omitted as any rod gear or lever can be used.

The bowl 75 extends beyond the flange 77 and flares outwardly and it is recessed from the inner side at the discharge end to form the pockets 88, these pockets having relief openings 89 through the discharge end of the bowl.

The relief openings 89 are closed by the slide valves 90 which are pivotally connected through the stems 91 to the sleeve 86, therefore when the sleeve 86 is operated both the ball valve and slide valve are removed from the relief openings, so that the heavier material is expelled from the bowl during the rotary movement.

The skimmer 83 is supported at intervals from the bowl and extends in sections or spouts from a point adjacent the outer wall of the bowl beyond the inturned flange 92 at the top of the bowl and is spaced from said flange to form the liquid passage 93 to a recovery turbine 94, that is to say, the annular outlet is formed by passages between turbine blades 95, which materially contribute to the maintenance of the momentum of the bowl during rotation.

The bowl may be driven by a primary turbine member 96 introduced in the path of the feed of material to the bowl, this primary turbine member 96 having the directing blades 97 forming passages leading to the impact face members 98 which are impinged by the liquid in its flow under pressure.

The inner deflecting shell 99 is mounted on the shaft 76 by suitable hub and arms and may or may not rotate independently of the bowl 75. This shell limits the depth of the liquid progressing towards the discharge and also carries drag links or pushers 100 sweeping the solids into the pockets 78 and spiral flexible scraper 102 and has holes 103 to permit liquid to enter said shell.

The pockets 88 have their entrance openings in the direct passage of the liquid along the wall, so in that portion of the machine it may not be necessary to have any pushing or scraping means for sweeping the solids into the pockets though this may be provided if it is found desirable.

In the operation of this invention, the material is fed in to one end, and in the preferable form of the machine comes in contact with the acceleration and distributing member 101 at the bottom of the inner shell.

In the beginning, the great body of liquid is held to the depth determined by the central opening in the head, thus the inner level of this hollow column of liquid partially fills the shell, usually with a light waste liquid which remains dead behind the light shell, thus stabilizing it by a constant wall of liquid.

The reduction of the speed of the shell by carrying forward the scrapers, facilitates the progress of heavier material which eventually reaches the line of the pockets, around the inner wall, which is swept out of the path of fresh liquid by the drags or pushers to fill the pockets, which are relieved at intervals by the movement of the sliding sleeve, through the opening of the relief openings by the removal of the valves operated by the stems and rocker arms connected to said sleeve.

The treated liquid continues flowing outwardly and passes through the inside recovery turbine impinging on the blades or divisions and on behind the skimmer, into the outer recovery turbine where it is directed into delivery passages by centrifugal force.

The skimmer cuts off the foam or froth which passes the outside of the inside recovery turbine and this froth is eventually dissipated or reclaimed according to the particular separation which is being accomplished.

In the modified form of the invention, the operation is so nearly the same and hardly requires description, as the liquid passing along the wall of the bowl reaches a depth determined by the inner shell and intermediate inwardly projecting flange, thus the heavier material is caught by the intermediate pockets and the same pushing effect is accomplished by the shell below said flange.

The operation is continued above the flange and the lighter liquid passes behind the skimmer while floating foam or froth discharges over the skimmer.

The heavier material outside the flange is caught in pockets at the end of the casing and there relieved. Practically the same arrangement of valve operation is shown in the modified form of the invention, but the recovery turbine is at the rim of the outer casing, and this recovery turbine forms the outlet for the lighter material which in the manufacture of pulp is the liquid relieved from the heavier impurities and from the lighter impurities, but it is obvious that the machine may be used for separating other materials.

What I claim is:—

1. In a centrifugal separator, a rotary bowl and shaft mounting therefor, an inner shell having upper and lower inwardly extending flanges and a tubular shaft mounting journaled on said shaft and supporting the shell and a spiral flexible strip attached to said shell and rotating therewith, and adapted to engage the heavier material thrown to the inner wall of the bowl and facilitate the progression thereof from one end to the other.

2. In a centrifugal separator, a rotary bowl flaring outwardly from the feed end and having a central opening at the discharge end and an inlet through said feed end, an inner shell having inwardly extending flanges at each end and a tubular mounting and radial extensions from said mounting to the shell adapted to permit the inflow of the liquid through one end to the inner diameter or level of said opening in the head during rotation, a shaft supporting said bowl and extending through said tubular mounting, a deflector secured to the inner end of said shell mounting and opposing said inlet opening and adapted to direct the liquid to the inner wall surface of the bowl while increasing its linear velocity and coincidently retarding the speed of the shell, and means for driving said bowl.

3. In a centrifugal separator, a bowl having a central opening in the discharge end and an annular inlet at the feed end, an intake, means for driving said bowl connected to the source of material to be fed into the machine

and having an annular chamber communicating with the bowl inlet, means for distributing and accelerating the inflowing liquid, means for regulating the depth of the liquid being treated, means introduced in the path of the discharge for supplementing the aforesaid driving means and for effecting an outlet, and means for skimming this lighter material at the discharge.

4. In a centrifugal separator, a bowl closed at one end and having an annular inlet and a central free opening at the other end, and annular discharge passages surrounding said free opening and forming impinging surfaces meeting the outflow and adapted to maintain the momentum in the rotation of the bowl, a shaft carrying said bowl and means for driving said shaft.

5. In a centrifugal separator, a main shaft, a bowl having shaft bearings, an annular feed inlet at one end and a central discharge outlet at the other end, outlet passages from said discharge end, and pockets with relief openings through the side of the bowl, valves closing said openings, a valve gear connected with said valve, including valve stems and rocker arms, pivotally supported from said shaft, a cam slidably mounted on said shaft having a pin extending inwardly therefrom in a slot in said shaft, and an operating rod introduced into said shaft and slideable therein and engaging said pin, and means for driving said casing.

6. In a centrifugal separator, a main shaft, a bowl mounted on said shaft and suitably driven, a shell contained within said bowl and supported from a tubular mounting having radial extensions and openings through said extensions, an axially adjustable journal member mounted on said shaft and supporting said tubular mounting of said shell, and having an annular flange therefrom engaging the mounting of said shell and bearing therefor, said bowl and said shell flaring outwardly from one end in parallel or nearly parallel directions forming an incline in the direction of the discharge end, means for feeding liquid under pressure to the feed end, means for varying the speed of said shell in respect to said bowl, and means for maintaining a constant speed in the rotation of said shell in relation to the speed of the bowl.

7. In centrifugal machines, a bowl suitably mounted and driven, an inner shell mounted to rotate at a different speed from the bowl, and adjustable to regulate the depth of the liquid treated centrifugally, means for progressing subsided particles towards the outlet end of the bowl attached to said shell and means for adjusting the inner shell axially in varying the depth of said liquid.

8. In centrifugal machines, a conical bowl suitably driven, a shaft mounted on said bowl, an inner conical shell having a tubular mounting journaled on said shaft, a threaded

sleeve screwed on to said shaft and forming a bearing and adjustable support for said tubular mounting, and means of varying the distance between said shell and said bowl by moving the shell and its mounting axially.

9. In centrifugal machines, a bowl having a feed inlet member extending thereinto and a contracted discharge opening, a skimmer suitably distanced in relation to said discharge to remove the lightest effluent in the separation and formed of a plurality of spout like sections and means for driving said bowl.

10. In centrifugal machines, a bowl suitably mounted and driven, an inner shell coaxially and rotably mounted in relation to the bowl and having inwardly projecting flanges, one flange at the outlet end having an inner diameter less than the diameter of the outlet from the bowl and the other flange having a diameter greater than the outlet of the bowl and so formed as to permit liquid to enter said shell and carry an accumulation of light floatable impurities within said shell.

11. In centrifugal machines, a bowl suitably mounted and driven, flexible scraper members, an inner member carrying said scraper members and coaxially and rotatably mounted in relation to said bowl, a suitably shaped acceleration member secured to said inner member and receiving the inflowing liquid and discharging it peripherally at increased velocity and with coincidental retard ing torque on the said acceleration and deflecting member.

12. In a centrifugal separator, a rotatable bowl suitably mounted and driven, a spiral spring member fastened at the ends independently of the bowl and held thereagainst from within, means to move said spring member over the surface of the bowl for facilitating the progression of subsided material along the bowl wall from one end to the other end, and outwardly recessed outlets from the bowl wall, at intervals circumferentially for relieving the bowl of the heavier material during rotation.

13. In a centrifugal separator, a rotary bowl suitably mounted and driven and having valve seats in a circular row surrounding ports forming relief openings beyond the bowl periphery and adjacent to the outlet end, valves closing said relief openings, rod gears operating said valves and means for pushing subsided material to reach said valves and ports.

14. In a centrifugal separator, a rotary bowl suitably mounted on a shaft and driven, an inner shell having a mounting independently journalled on said shaft and open to the incoming material at the top and bottom suitably supported away from the bowl inlet at the feed end, and a spiral spring scraper secured to each end of the shell and free therebetween for the progression of the

material from one end to the discharge end in the bowl.

15. In a centrifugal separator, a bowl having an inlet opening at one end, and a cover surrounding a central discharge, an adjustable inner shell opposing said inlet opening, a rotary driving member in said inlet opening and a rotary driving member at said discharge opening operated by the flowing contents.

16. In a centrifugal separator, a main shaft, a bowl suitably mounted on said shaft and flaring outwardly towards the discharge end having an inlet at the feed end, outlet openings at the discharge end and pockets with relief openings, valves closing said relief openings, a valve gear connected with said valve, a slideable cam mounted on said shaft suitably operated, connecting rods reciprocated and operatively associated with said cam and engaging said valves, and means for driving said casing.

17. In a centrifugal separator, a main shaft, a bowl suitably mounted and rotated, an adjustable inner shell within said bowl and spring scrapers carried therewith, a dish shaped deflector secured to said shell at the end opposing the inlet into said bowl, and having its wall extending in the direction of the inner wall of said bowl, and means for driving said bowl.

18. In centrifugal separators, a bowl suitably mounted and driven and having an annular chamber and discharge pockets at intervals from said chamber, a rotatory scraper operatively mounted and rotating at a variable speed to the bowl and a drag link carried by the scraper mounting and gathering the subsided particles toward pockets.

19. In centrifugal machines, a bowl suitably mounted on a driven shaft, an inner rotating shell adjustable lengthwise and turning on the bowl shaft and a differential gear mechanism driving the shell at speeds variable to the bowl and in the same direction.

20. In centrifugal machines for the continuous treatment of fluid mixtures of solids and liquids, a bowl suitably mounted for rotation and driven, an inlet and an outlet for the main fluid stream and outlets for sinkable and floatable rejections, scraper means adapted to sweep sinkable rejections over the inner surface of the bowl to storage wells in the wall of the bowl, outlet ports from said wells with closures, means to operate said closures intermittently during the rotation of the bowl for the intermittent ejection of sinkable particles through said ports and skimming spout means for the continuous ejection of floatable rejects from the bowl.

21. In a machine for removing impurities from fibrous vegetable pulps in aqueous suspension, means for continuously feeding the

pulp mixture into a revolving centrifugal separating bowl and thereby causing the mixture to revolve therewith at a speed sufficient to effect rapid subsidence of sinkable rejections 5 and the rapid flotation of floatable rejections, means for guiding the flow of the mixture within the bowl through a separating region, including a shallow frusto-conical member delivering an annular stream continuously, and removing floatable rejections from the bowl, means for intermittently removing sinkable rejections from the bowl during separations and means for continuously discharging the purified 10 mixture from the bowl at a velocity less than its peripheral velocity within the separating regions.

22. In a centrifugal separator, a bowl rotatably mounted and forming an intermediary collecting member in the course of a continuously flowing stream and having an annular or ring cover at the outlet and forming an open discharge and a central inlet at the other end, a shell of corresponding 25 shape to the bowl independently rotated and forming therewith an annular settlement chamber and lighter liquid discharge, a spring scraper member attached to the shell and progressing the heavier material during 30 the operation, means for driving the bowl and incidentally turning the shell, and valves recessed in the bowl wall adjacent to the outlet end and operated intermittently in relation to the continuous operation of the bowl.

35. 23. In centrifugal machines, a main shaft, a bowl having an inlet at one end and an outlet at the other end and mounted on said shaft, an inner shell independently mounted on said shaft and longitudinally adjustable 40 to vary the cubic contents of liquid treated in an annular chamber between the shell and the bowl according to selection and in agreement with the centrifugal action on the particular liquid substance treated and means 45 for rotating said bowl and shell.

24. In a centrifugal separator, a rotary bowl suitably mounted and driven and having an outstanding flange at the outlet and supporting a ring cover and forming an 50 annular channel for the heavier substance and from the bed of said channel outlet nipples valve controlled and arranged at intervals throughout the length of said channel, a rod valve gear operated coincidently with 55 the driving mechanism and intermittently opening said nipples, and an inner shell independently mounted and driven at a varying speed from said bowl and forming a separating chamber with the bowl wall and 60 an inwardly extending discharge passage to the open end of the bowl for the lighter liquid substance.

25. In a centrifugal separator, a bowl suitably mounted and driven to rotate about a 65 central axis, an inlet spout thereinto, a dis-

charge outlet in one end, discharge ports in the periphery of the bowl, a flexible scraper strip spirally wound within the bowl and attached at its extremities to an inner mounting journaled to rotate independently of the 70 bowl, said flexible scraper strip being free between its points of attachment to the inner mounting and adapted to hug the inner surface of the bowl by the action of centrifugal force, and means to rotate the scraper and its 75 mounting at a speed different from that of the bowl.

Signed at Montreal, Canada, this 13th day of March, 1930.
